UNITED STATES PATENT OFFICE.

HORACE G. KITCHELL, OF GREENWOOD, MISSISSIPPI, ASSIGNOR TO DELTA MACHINE WORKS, OF GREENWOOD, MISSISSIPPI.

MECHANICAL MOVEMENT.

Application filed May 5, 1920. Serial No. 379,061.

To all whom it may concern:

Be it known that I, HORACE G. KITCHELL, a citizen of the United States, residing at Greenwood, in the county of Leflore and 5 State of Mississippi, have invented certain new and useful Improvements in Mechanical Movements, of which the following is a specification.

This invention relates to certain new and 10 useful improvements in mechanical movements, and it has for its objects among others to provide a new and useful movement applicable in many ways, to many uses and among which may be mentioned 15 airships, automobiles, marine vessels, elevators, tools, shafting, or, in fact, almost any and all positions and places and under almost all conditions where it is desired to obtain greatly increased speed. The improvement as hereinafter disclosed is capable of use in connection with shafting either line or angular and in cases where a multiplicity of shafting is desirable or required.

25 It has for a further object to provide an improved movement of this general nature in which the parts shall be few in number, those compactly arranged, readily assembled, or disassembled for repairs or other 30 purposes, not liable to get out of order or become damaged and yet which shall be most efficient in operation. It is well adapted also for use in auto-trucks and the like where great power is required under reduced speed.

35 Other objects and advantages of the invention will hereinafter appear and the novel features thereof will be particularly pointed out in the appended claims.

The invention is capable of embodiment 40 in a variety of forms, for varied uses, some of which only are herein illustrated.

The invention, in such preferred forms, is clearly illustrated in the accompanying drawings, which, with the numerals of reference marked thereon, form a part of this specification, and in which—

Figure 1 is a front elevation, with a portion broken away, showing one form of an embodiment of my invention.

50 Figure 2 is a reverse view with the shaft in cross section.

Figure 3 is a front view with portions broken away, showing a modified form.

55 Figure 4 is a vertical section on the line 4—4 of Figure 1.

Figure 5 is a front face view of the main driven element removed from its casing.

Figure 6 is an edge view thereof.

Figure 7 is a front view showing a modified form of drive.

Figure 8 is a face view of the reverse side of the device, showing another form of drive.

Figure 9 is a substantially central section at right angles to the shafts, showing a 65 still further form of embodiment of the invention.

Figure 10 is a section, as on the line 10—10, of Figure 9, looking in the direction of the arrows with parts in elevation.

Like numerals of reference indicate like parts throughout the several views in which they appear.

In carrying out my invention, in the various forms, the same generic principle is 75 adhered to. This embodies a cooperative arrangement or disposition of what is known in the art as a trammel, and a system of gears of whatever form and arrangement I may choose, and means whereby the element 80 carrying the blocks which travel in the radial grooves of the trammel mechanism is employed as the driving member. With this general understanding of my present invention, I will now proceed to describe 85 the various forms of embodiment thereof, attention being first directed to Figures 1, 2, 4, 5 and 6, in which 1 is a casing chambered, as at 2, to receive the operative parts and provided with a cap plate 3 secured 90 thereto by bolts or other means 4 provided for ready access to the enclosed parts when necessary. The casing 1 is provided with a hub 5 and the cap plate 3 is provided with a coaxial hub 6, as seen best in Figure 4. 95

In the form illustrated in Figures 1, 2, 4, 5 and 6, 7 is a shaft. Carried by this shaft is a gear 8, in this present instance shown as having a hub 9 fitted within a socket 10 within the hub 5.

100 Within the chamber 2 of the casing is the disc or trammel member 11 provided upon the one face with a plurality of radial channels 12, in this instance shown as four in number, although this number may be varied 105 within any reasonable limit. These channels are undercut, as shown in Figure 6, as is usual in this class of devices and designed to travel therein are blocks 13 pivotally mounted upon suitable means, as the screws 110

14, in the disc 15 fast upon which is a gear 16 having an axial opening 17 which is adapted to receive a pin 18 fixed in the front wall of the casing 1, as seen clearly in Figure 4.

By reason of the blocks 13 being pivotally mounted on the disc 15 they act as levers against the gear 16, and as one block is being actuated by the disc 11 at its periphery, its mate, that is the other block, is passing the center of the disc 11 without resistance, and by reason of the lever action and the greater rapidity of motion of the block at the center I obtain a differential motion, not a planetary motion, as the pin 18 will prevent any planetary motion, although the benefits derived are substantially the same as derived from a planetary motion and the two shafts are kept in perfect alinement without which such differential motion could not be obtained.

These parts are all arranged within the casing 1 and the cap 3 is then applied, by preference the parts being designed to run in oil for an obvious purpose. The number 11 is shown as provided with a hub 19 in which is fixed a shaft 20, as shown in Figure 4, designed to be revolved from any suitable source of power, not shown.

The operation of this form is as follows: motion being imparted to the shaft 20 from any suitable source, the revolution of this shaft imparts positive rotary motion to the member 11, and as this member is revolved it imparts rotary motion to the disc 15 and its gear 16, through the medium of the radial channels and the blocks of the trammel, as will be readily understood. It is desired to state here, however, that during the revolution of the member 11 the disc 15 and its gear 16 remain relatively stationary, that is, as to position within the casing, or, in other words, the disc 15 and the gear 16 do not have a planetary movement. Revolution of the disc 15 and gear 16, however, by reason of the interengagement of the gear 16 with the gear 8 on the shaft 7 imparts rotary motion to the latter. However, by this arrangement of parts, the gear 16 will be given two complete revolutions to one revolution of the shaft 20, that is with four radial grooves of the trammel, but if a greater number of grooves is employed the number of relative revolutions of the disc 8 will be proportionately increased, this being accomplished by reason of the radial movement and the fact that the gear 16 is not planetary.

As hereinbefore stated, this generic principle may be embodied in a variety of forms, the variations being mainly as to the drive. For instance, in Figure 3 I have shown, in lieu of the two intermeshing gears 8 and 16, a sprocket wheel 21 on the shaft 7 and a sprocket wheel 22 on the stud or pin 18, the two sprockets being connected by means of a

sprocket chain 23, whereby revolution of the disc 15 imparts rotary motion to the shaft 7, the remainder of the device being the same as hereinbefore described in connection with Figure 4, except that the shafts 7 and 20 in the form shown in Figure 3 revolve in the same direction instead of in reverse directions as in Figure 4.

In Figure 7 the disc 24, which is the equivalent of the disc 11 in the forms hereinbefore described, is toothed peripherally, as seen at 25, and meshing with this toothed periphery 25 is a worm 26 carried by a shaft 27 designed to be revolved from any suitable source of power, it being understood that this shaft and its worm is the equivalent of the shaft 20 in Figure 4 and serving to drive the disc 11, the other parts being of the same construction and arrangement as shown in Figure 4.

The disk 11 or its equivalent member 28 shown in Figure 8, may be provided with an internal gear 29 with which meshes the gear 30 carried by a shaft 31 driven by any suitable source of power, not shown. Revolution of the gear 30 by its engagement with the internal gear 29, serves to rotate the disc 28 in the same manner as the shaft 20 rotates the disc 11 in Figure 4.

The disc which constitutes the driving member of the device may, in some instances, be provided with an internal gear 32 just inside of its periphery, as seen in Figure 4, with which may be caused to engage a pinion similar to the pinion shown in Figure 8, and, in some instances, this disc may be provided with an internal gear 33 about the axis of the disc, as shown in Figure 4, with which also may engage a pinion or gear for a like purpose. Either one or both of these may be used, as circumstances may require.

As shown in Figures 9 and 10, the disc 34, which is the equivalent of the disc 11 in Figure 4, may be provided with a peripheral bevel gear 35 with which meshes a bevel gear 36 carried by a shaft 37, the equivalent of the shaft 20 in Figure 4, and revolved from any suitable source of power, not shown. It is to be understood that the disc 15, with its gear 16 and its blocks 13, engaged in radial grooves in the disc, are all employed the same as in the other forms. I also may combine with this form shown in Figures 9 and 10, sprocket wheels 38 and 39 connected by a sprocket chain 40, upon one side of the disc, while upon the other side I employ the gear 41 which is the equivalent of the gear 16 in Figure 4, and the gear 42 which is the equivalent of the gear 8 in Figure 4, the latter being carried by a shaft 43 to which rotary motion is imparted, as will be understood. In this latter form, the two shafts 43 and 44 are revolved in the same direction. It is to be understood that in all of

the forms the disc and its associated parts are enclosed within a suitable casing such as that described in connection with Figure 4.

5 From the foregoing, it will be clearly understood that I have devised a simple and efficient mechanical movement, the generic feature of which is capable of embodiment in a multiplicity of forms, and while these 10 structural embodiments of the invention which are herein disclosed are what I at the present time consider preferable, it will be clear that the same is subject to changes, variations and modifications in detail, proportion of parts etc., without departing from the spirit of the invention or sacrificing any of its advantages. I, therefore, do not intend to restrict myself to the precise construction herein shown, described and 15 claimed, but reserve the right to make such changes, variations and modifications as come properly within the scope of the protection prayed.

What is claimed as new is:—

25 1. A reduction gear comprising a trammel element having slots, a second trammel

element arranged to be rotated thereby, a gear element carried by the latter and rotatable therewith, a shaft coaxial with the first-named trammel element, a gear element movable therewith and cooperating with the first-named gear element, a casing, and means thereon for supporting the driven shaft and the second-named trammel element. 30 35

2. A reduction gear comprising a trammel element having slots, a second trammel element arranged to be rotated thereby and provided on one of its faces with a gear element, a shaft coaxial with the first-named 40 trammel element having a gear element cooperating with the first-named gear element, and a casing for said mechanism comprising a base plate having a journal bearing for the shaft of the first-named trammel 45 element, a cover plate having a gudgeon pin to support the second trammel element and its gear element, and a journal for the driven shaft.

In testimony whereof I affix my signature.

HORACE G. KITCHELL.
